UNITED STATES PATENT OFFICE

WILLIAM R. SWAIM, OF HASKELL, TEXAS

TYPEWRITER COVER

Application filed March 19, 1931. Serial No. 523,897.

This invention relates to covers or the like, and more particularly to a cover adapted to be used in connection with a typewriter or the like.

5 A object of this invention is to provide a cover of this kind which may be readily mounted or positioned about the typewriter and readily moved into operative or inoperative position, the cover being so constructed that when in inoperative position, it will take up a relatively small space back of the typewriter.

10 Another object of this invention is to provide in combination with a cover of this kind means whereby the lower portion of the cover is held away from the keys of the machine so as not to interfere with the normal use of the machine.

15 A further object of this invention is to provide a cover of this kind which is adapted to have one portion thereof attached to the typewriter at the bottom thereof so as to entirely cover the bottom of the typewriter, the other or top portion being foldable and held in folded or rolled condition at the back of the typewriter when the cover is not disposed over the typewriter.

20 The above and various other objects and advantages of this invention will in part be described in and in part be understood from the following detailed description of the present preferred embodiment, the same being illustrated in the accompanying drawings, wherein:

25 Figure 1 is a sectional view taken substantially through the center of the device constructed according to the preferred embodiment of this invention mounted on a typewriter;

30 Figure 2 is a sectional view showing the device in folded or open position;

35 Figure 3 is a bottom plan view of the bottom of the device;

40 Figure 4 is an enlarged fragmentary front elevation showing the means for locking the sections of the device together, and

45 Figure 5 is a fragmentary detail elevation of one of the strap members for holding the device in folded or open position.

50 Referring to the drawings wherein like

numerals of reference designate corresponding parts throughout the several views, the numeral 10 designates generally a conventional typewriter having a finger board 11 and a plurality of supporting feet 13. Where typewriters are secured to a desk having a rockable leaf or support, the typewriters are usually left uncovered and any dust raised about the desk settles in the typewriter, and in sections of the country which are subject to sand storms or the like, the sand seeps into the working parts of the typewriter and interferes with the smooth operation thereof. In like manner, where typewriters are covered with a conventional cover having no closed bottom, the sand and dust seeps into the working parts of the machine and interferes with the smooth operation thereof.

55 In order to adequately protect the typewriter when it is not in use, I have provided a typewriter cover generally designated as 12, which is of flexible construction and may be constructed of cloth such as canvas or rubberized material of a relatively flexible 60 construction so that it may be readily rolled or folded when the typewriter is in use.

65 The cover 12 comprises a base portion 14 which is of a configuration conforming to the configuration of the bottom of the typewriter including the finger board portion 11, and this base portion 14 is provided with a plurality of spaced apertures 15 for receiving the bolt used for securing the feet 13 to the bottom of the typewriter 10. In this manner, 70 the base 14 is permanently attached to the bottom of the typewriter. The forward end 75 of the base 14 extends substantially to the forward edge of the finger board 11, and this forward edge is free as well as the side edges of the base 14.

80 Attached at the rear edge of the base 14 is a top or cap member 16 which is of a configuration conforming substantially to the configuration of the body portion of the typewriter and is of a size to loosely engage about the body of the typewriter including the sides, front and rear and top thereof. This cap or top portion 16 may be formed integrally with the base 14, and the marginal 85 90 95 100

edges of the top 16, together with the marginal edges of the base 14, are provided with conventional zipper elements 17 and the conventional zipper locking and releasing member 18. Preferably, there are two of these releasing members 18 and the releasing members 18 are brought forwardly to the front of the base 14 at substantially the central portion thereof.

10 Adjacent the rear of the base portion 14, there are provided a plurality of straps 19 which are mounted on the base 14 in spaced relation to each other, these straps 19 having one portion 20 of a clasp and the other complementary portion of the clasp 21 is attached to the back of the top 16 so that when the top 16 is lifted off of the typewriter and rolled or folded at the back of the typewriter, the strap 19 will hold the cover in folded or 20 rolled condition.

25 In order to hold the front portion of the base 14 away from the keys of the typewriter 11, I have provided a plate member 22 which has spaced openings therethrough adjacent the rear edge thereof whereby to receive the pegs of the feet 13 so as to secure this plate 22 in position beneath the bottom of the finger board 11. The plate 22 is bent downwardly so as to space the forward edge of the plate 30 downwardly from the lower edge of the finger board 11 and to hold the flexible bottom member 14 away from the keys and spacing bar of the typewriter 10. The plate 14 is bent downwardly and forwardly at a point closely 35 adjacent the pegs or feet 13.

40 It will be obvious from the foregoing that a relatively simple but at the same time practical cover has been devised by means of which the entire typewriter including the bottom thereof may be thoroughly encased in the cover or closure 12 so that when the typewriter is not in use, it will be thoroughly protected from dust, dirt or the like.

45 In the use of this device, the bottom 14 is permanently interposed between the feet 13 and the bottom of the typewriter 10, and when the typewriter is not in use, the cover or top portion 12 may be extended over and about the typewriter 10 and secured in this 50 position by means of the zipper elements 17 by drawing the zipper releasable locking member 18 forwardly to the front of the base 14.

55 When it is desired to use the typewriter, the zipper releasing elements 18 may be moved to the rear of the base 14, and the top element or member 16 may be folded or rolled at the rear of the typewriter and secured in this position by means of the strap members 19.

60 It is, of course, understood that various changes and modifications may be made in the details of construction and design of the above specifically described embodiment of 65 this invention without departing from the

spirit thereof, such changes and modifications being restricted only by the scope of the following claims.

I claim:

1. A cover of the character described comprising a base having a plurality of spaced apertures adapted to receive bolt members carried by a typewriter, a flexible top integrally formed with one edge of the base and a plate member engaging the base and the front leg bolts of the typewriter, and interposed between the base and the bottom of the typewriter whereby to hold one portion of the base away from the key elements of the typewriter, and means carried by the top and the base for securing the top in position over the typewriter.

2. A cover of the character described comprising a substantially rectangular base having a plurality of spaced apertures adapted to engage the leg bolts of a typewriter whereby to secure the base beneath the typewriter, a hood member integrally formed with the base and having the side and front edge portions thereof free from the base whereby to permit rolling of the hood at the back of the typewriter, strap members carried by the base adjacent the back thereof, and clasp members carried by the hood and the straps whereby to hold the hood in rolled position at the back of the typewriter.

In testimony whereof I hereunto affix my signature.

WILLIAM R. SWAIM.
